(57) **CLAIM**

The ornamental design for a light fixture, as shown and described.

DESCRIPTION

FIG. 1 is a top perspective view of a light fixture. FIG. 2 is a bottom perspective view of the light fixture of FIG. 1.

FIG. 3 is a front view of the light fixture of FIG. 1.

FIG. 4 is a rear view of the light fixture of FIG. 1.

FIG. 5 is a left side view of the light fixture of FIG. 1.

FIG. 6 is a right side view of the light fixture of FIG. 1.

FIG. 7 is a top view of the light fixture of FIG. 1.

FIG. 8 is a bottom view of the light fixture of FIG. 1.

FIG. 9 is a top perspective view of a light fixture.

FIG. 10 is a bottom perspective view of the light fixture of FIG. 9.

FIG. 11 is a front view of the light fixture of FIG. 9.

FIG. 12 is a rear view of the light fixture of FIG. 9.

FIG. 13 is a left side view of the light fixture of FIG. 9.

FIG. 14 is a right side view of the light fixture of FIG. 9.

FIG. 15 is a top view of the light fixture of FIG. 9; and,

FIG. 16 is a bottom view of the light fixture of FIG. 9.

The broken lines shown on the drawings depict portions of the light fixture that form no part of the claimed design.

1 Claim, 16 Drawing Sheets
